UNITED STATES PATENT OFFICE.

JOHN P. NEFF, OF EAST ORANGE, NEW JERSEY, ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER FIRE-BOX.

1,138,058.

Specification of Letters Patent.

Patented May 4, 1915.

Application filed October 1, 1913. Serial No. 792,783.

To all whom it may concern:

Be it known that I, JOHN P. NEFF, a citizen of the United States, and a resident of East Orange, county of Essex, New Jersey, have invented certain new and useful Improvements in Locomotive-Boiler Fire-Boxes, of which the following is a specification.

My invention relates to improvements in locomotives, and has particular reference to improvements in fireboxes of locomotive boilers.

The object of my invention is to provide a locomotive boiler firebox in which the fuel shall be completely and perfectly consumed before the products of combustion escape through the flues; to provide a firebox wherein the burning gases may complete their combustion in a chamber substantially 15 completely screened from the main combustion chamber of the firebox; in which the gases of combustion shall be commingled with additional air before entering the auxiliary combustion chamber; and in which access to the auxiliary combustion chamber 20 can be obtained without destroying or removing the upper part of the refractory screen.

A further object of my invention is to provide a transverse refractory screen for the fireboxes of locomotives, the lower part of which shall prevent the direct flow of the gases of combustion from the fuel bed to the flues and the upper part of which shall permit the flow of gases forward in the firebox, and which shall be so constructed that access to the space forward of the screen may be easily attained.

My invention resides in a locomotive firebox provided with a transverse refractory screen extending from the grate to the crown sheet, the lower part being imperforate, the upper part being perforate, and a removable slab arranged between the upper and lower parts whereby access to the space forward of the screen may be easily attained.

My invention also consists in a firebox provided adjacent to its forward end with an imperforate refractory wall spaced from the flue sheet and rising substantially half the height of the firebox, and an open-work refractory screen offset rearwardly from the wall and extending from the level of the top of the wall to the crown sheet, the space between the lower edge of the screen and the

top of the wall being closed by horizontally arranged refractory slabs, and means for supporting the screen in position.

My invention also consists in the various constructive details and arrangements of parts, whereby the above and other objects are attained and all as hereinafter described and particularly pointed out in the appended claims.

My invention will be more readily understood by reference to the accompanying drawings, forming a part of this specification, and in which:

Figure 1 is a central, vertical, longitudinal section of a locomotive boiler firebox equipped with a refractory divisional wall arranged in the forward part thereof and embodying my invention; Fig. 2 is a vertical, transverse section of the firebox on the line 2—2 of Fig. 1; Fig. 3 is a view similar to Fig. 2 showing a slight modification of my invention; Fig. 4 is a detail, vertical section of the wall shown in Fig. 3; Fig. 5 is a view similar to Fig. 2 showing another modified form of my invention; Fig. 6 is a view similar to Fig. 4 taken on the line 6—6 of Fig. 5; Fig. 7 is a perspective view of one of the bricks forming the perforate screen illustrated in Figs. 3 and 4; Fig. 8 is a perspective view of one of the bricks of the screen shown in Figs. 5 and 6; and Fig. 9 is a perspective view of one of the bricks forming the screen shown in Figs. 1 and 2.

In modern locomotive development it has been found necessary to gradually increase the strength of the draft so that sufficient fuel might be consumed upon the grates to properly supply the locomotive with steam. This exceedingly strong draft serves not only to raise and carry upward through the firebox solid fuel particles, cinders and ash, but also causes the gases to flow at such a high speed from the fuel bed to the flues that it has been substantially impossible for the fuel to be completely consumed before the gases escape through the flues.

It is a particular object of my invention to, in a sense, increase the capacity of the firebox rather than diminish it, to cause the firebox gases to give up their heat efficiently to the water in the boiler and to protect the gases in the final stage of their combustion within a highly heated chamber substantially separate from the main combustion chamber so that the fuel may be completely

burned before the gases escape through the flues. To this end I have divided the firebox by means of a refractory baffle or screen into an auxiliary combustion chamber in the forward end, and a main combustion chamber at the rear end. This screen extends from the level of the grate to the crown sheet, the lower part thereof is solid or imperforate and is adapted to inject air into the firebox above the fuel bed, the upper part of the screen is provided with many passages through which the gases of combustion can pass from the main combustion chamber to the auxiliary combustion chamber, and this wall is also built of refractory parts, the result being that the upper part of the wall, being made of parts which are thin and light, soon attains a high temperature, or, in fact, the maximum temperature of the firebox, and thereafter serves to ignite the gases and the fuel particles which may come into contact therewith and at a temperature below that of proper combustion. Furthermore, the auxiliary combustion chamber being separated from the main chamber by means of this refractory screen which becomes highly heated, the auxiliary combustion chamber is protected against the entrance of drafts of cold air through the fire-door and the gases therein are maintained at a temperature high enough to prevent any of the fuel escaping from the firebox unburned. Again the auxiliary combustion chamber being relatively large, the speed of the gases through this chamber is reduced below that at which they flow through the screen and, consequently the gases deposit or drop their burden of cinders or ashes in the auxiliary combustion chamber before they enter the flues, thus preventing the ejection of the unburned or solid particles from the stack of the locomotive. In order to provide a sufficient grate area and at the same time provide an auxiliary combustion chamber of the requisite capacity, I arrange the lower part of the screen nearer the flue sheet than the upper part, and for the purpose of providing an entrance through which access can be gained to the auxiliary combustion chamber to effect necessary repairs, I arrange slabs closing the space between upper and lower parts of the screen, in such a way, that they may be easily removed to provide an opening through which a workman may enter the auxiliary combustion chamber from the main combustion chamber.

In order to support the upper part of the screen in position, I provide water-circulating tubes extending transversely of the firebox, from side sheet to side sheet and beneath the wall tying these tubes and the wall together by means of the refractory slabs.

25 A firebox A, as shown in the drawings,

comprises a flue sheet a¹ at the forward end, a rear sheet a², side sheets a³ and a crown sheet a⁴. Flues a⁵ lead forward from the flue sheet and the rear end of the firebox is provided with a fuel door or opening a⁶. I 70 arrange a transverse metallic wall support B extending across the firebox from side to side and spaced rearwardly from the flue sheet, and upon this support I erect a solid or imperforate wall C also extending across 75 the firebox. This wall serves to prevent the direct flow of the gases of combustion from the fuel bed to the flues. A grate D of usual construction fills the space between the wall C and the rear end of the firebox. I close 80 the forward end of the firebox by means of a horizontal plate a⁷ which also serves to close the lower end of the auxiliary combustion chamber a⁸ which is formed between the wall and the flue sheet. The wall C is 85 preferably made up of a number of horizontal rows c¹ of bricks c². In the form illustrated in Figs. 1 and 2, the wall consists of two of these rows and the wall extends 90 substantially half way from the grate to the crown sheet. I fill in the space between the upper part of the wall and the crown sheet with a perforate wall E, and while the upper part might be arranged in other relations to the lower part, I preferably space it 95 rearwardly from the main wall C, thus enlarging the auxiliary combustion chamber a⁸. To support the wall E in its position I provide transversely extending water-circulating tubes F, which extend from side sheet 100 to side sheet, the opposite ends of each tube being spaced vertically relatively to each other so that each tube will be inclined and will cause a current of water to be maintained through these tubes at all times. 105

The wall E consists of a plurality of bricks c¹, which may assume many different cross sections, but which, in any event, are so arranged or placed in relation to each other that the wall is provided with many 110 transverse openings c² between the various bricks, and which openings serve to permit the gases of combustion to flow forward from the main combustion chamber a⁹ which occupies the space between the refractory 115 screen and the rear end of the firebox to the auxiliary combustion chamber. For the purpose of providing a suitable foundation upon which to build the perforate screen E, I provide refractory slabs e¹ which are 120 adapted to rest at their rear ends upon the tubes F and at their forward ends upon the upper surface of the wall C. These slabs are preferably provided with depending portions e² on their lower sides adapted to contact at their rear ends with one of the tubes F and at their forward ends with the rear face of the wall C, and these slabs are thereby maintained in position and 125 serve to brace or steady both the wall C and 130

the tubes F. For the purpose of permitting access to the auxiliary combustion chamber, I provide a refractory bridge member e⁵ adapted to rest upon the slabs e³ and long enough to span the center slab e⁶. This bridge is cut away on its lower surface above the center slab e⁶ in such a manner that the forward end of the slab e⁶ can be freely raised to permit the projection e⁴ to be disengaged from the wall C and then the slab e⁶ can be easily removed from its position, providing an opening of sufficient size through which a workman can gain access to the auxiliary combustion chamber. The wall E may be aptly termed a "refractory screen", for it is made up of the bricks e¹ and the alternating spaces e². These bricks, as shown in Figs. 1 and 2, are I-shaped in cross section and have relatively thin walls, These thin walls soon become highly heated, and their points of contact, one with another, soon become cemented together by reason of the high temperature to which they are exposed in use and by the melted slag which is deposited upon the bricks from the firebox gases. While under ordinary circumstances this cementing action is sufficient to retain in place the brick members of which the wall E is built, I prefer to interlock these members, and for this purpose I provide the upper edges of these bricks with projections e⁷ and their lower edges with notches e⁸ whereby the bricks are interlocked and are prevented from moving out of their positions. I provide the lower wall C with air inlet conduits c³ rising from the lower end thereof and entering the fire box adjacent to the upper edge of the wall through the rear face and below the slabs e³. The air thus entering through the wall C is partly heated and as it enters the firebox over the fuel bed and below the slabs e³ it is mixed with the firebox gases, and thereby raised to a higher temperature before it enters the main part of the main combustion chamber a⁸. This construction serves to add to the efficiency of the firebox, for the reason that the air being thus gradually mixed with the firebox gases does not tend to chill them to any appreciable extent. The wall support B is provided at its rear edge with a ledge or rib b¹ which aids in retaining the wall C upon its support. For the purpose of admitting air to the channels c³ I provide depending air inlets b² secured to the wall support B and adapted to permit the entrance of air into the conduits c³. I curve the lower ends of these inlets b² to project them forwardly and I provide their open ends with flaring mouths b³ through which the air is caused to enter said tubes b² with considerable force, when the locomotive is in motion. For the purpose of conveniently clearing the auxiliary combustion chamber

from the deposit of cinders and fuel particles which collects therein, I provided at its lower end a cinder outlet a¹⁰ which is normally closed at its lower end by a removable cover a¹¹.

In Figs. 3 and 4 I have illustrated a refractory screen H, made up of bricks h¹ which are D-shape in cross section instead of I-shape, and are provided in their lower edges with depending centrally arranged projections h², and on their upper surfaces with complementary sockets h³. These projections are adapted to enter the sockets of bricks immediately below them and thus retain the bricks of the wall in position against movement laterally in any direction. The weight of the bricks themselves serves to hold the wall from rising and hence the wall constructed in the manner described is substantially permanent even through the several bricks of which the screen is made do not completely cement together. In Figs. 5 and 6 I have shown another form of interlock. In this wall the bricks j¹ have their upper corners cut away to provide sockets j² and are provided on their lower surfaces with projections j³ adapted to enter the sockets j² when the bricks are arranged in position in the wall. These complementary sockets and projections prevent the movement of the individual bricks transversely relatively to the wall and hold them properly spaced apart longitudinally of the wall. They also serve to hold the bricks with sufficient rigidity in position until the wall has been once heated, the heating action serving to cement the individual bricks securely in position.

In all of the forms of my invention I preserve the main features which are a solid wall spaced from the flue sheet and rising from the level of the grate substantially half the height of the box, an upper screen spaced farther from the flue sheet and rising from the upper part of the wall to the crown sheet, and a refractory horizontal wall joining the upper part of the lower wall and the lower part of the upper wall, a portion of said horizontal joining wall being easily removable to give access to the auxiliary combustion chamber. A firebox constructed in accordance with my invention serves to permit the combustion or the burning of the fuel to nearly complete condition in the main combustion chamber and causes the further and complete burning of the fuel in a combustion chamber which is maintained at a relatively high temperature and is protected from incoming blasts of cool air, whereby the fuel may complete its combustion under conditions which result in substantially perfect results being attained in fuel consumption. Furthermore, the wall serves to retard the flow of the gases and retain them in the main combustion chamber

whereby they not only substantially complete the burning therein, but are caused to give up their heat most advantageously to the water of the boiler.

5 As many modifications of my invention will readily suggest themselves to one skilled in the art, I do not limit or confine my invention to the specific arrangements of parts or structures herein shown and described.

10 I claim:

1. In a locomotive boiler firebox, a refractory baffle extending from the grate to the crown sheet and from side to side in the firebox and spaced rearwardly from the flue sheet dividing the firebox into an auxiliary combustion chamber in the forward part, and a main combustion chamber in the rear part, the lower part of the baffle preventing the direct flow of gases from the fuel bed to the flues and the upper part comprising checker-work permitting the gases to flow forwardly from the main combustion chamber to the auxiliary combustion chamber, and transverse water circulating tubes extending from side to side of the firebox supporting said checker-work in position.

2. In a locomotive boiler firebox, a refractory wall extending across the firebox from the grate to the crown sheet and spaced rearwardly from the flue sheet, the lower part being adapted to prevent the flow of gases from the fuel bed to the flues and being provided with air inlet passages adapted to permit air to enter the firebox over the fuel bed, the upper part of the baffle being composed of a refractory wall having openings through which the gases of combustion may flow from the fuel bed to the flues and being offset rearwardly from the lower part, refractory slabs filling in the space between the lower part and the upper part, and said air inlets being adapted to inject air into the firebox beneath said slabs.

3. In a locomotive boiler firebox, a refractory baffle spaced from the flue sheet and adapted to divide the firebox into an auxiliary combustion chamber at the forward end and a main combustion chamber at the rear end, the lower part of said wall being arranged at the forward end of the grate and adapted to prevent the flow of gases from the fuel bed to the flues, the upper part of the wall being spaced rearwardly from the lower part and connected thereto by means of refractory slabs, means supporting the upper part of the wall in position, the lower part of the wall having air inlets through which air is admitted to the firebox beneath said slabs.

6. In a locomotive boiler firebox, a refractory baffle in the forward end thereof extending from the grate to the crown sheet and from side to side of the firebox and composed of a lower imperforate part and an upper part having gas passages to permit

the flow of gases from the fuel bed to the flues, the upper part being offset rearwardly from the lower part, transversely extending water-circulating tubes supporting the upper part in position, and refractory slabs resting at the rear ends upon said tubes and upon which the upper part of the wall is supported and resting at their forward ends upon said wall and serving to close the space between the upper part and lower part of the baffle, one of said slabs being easily removable to permit entrance to the space between the baffle and the flue sheet.

5. In a locomotive boiler firebox, a cross wall rising from the grate to substantially half the height of the firebox and spaced from the flue sheet, transversely extending water-circulating tubes arranged in the firebox spaced rearwardly from the upper edge of said wall, refractory slabs resting at their rear ends upon said tubes and at their forward ends upon said wall and closing the space between the tubes and the wall, an auxiliary wall resting on said slabs and rising to the crown sheet, said auxiliary wall being provided with gas passages to permit the flow of gases from the fuel bed to the flues, a refractory bridge member resting on said slabs and serving to support said wall, said bridge member spanning one of said slabs and being provided on its underside with a recess permitting the free removal of said spanned slab.

6. In a locomotive boiler firebox, a refractory cross wall arranged in the forward end thereof spaced rearwardly from the flue sheet and rising to substantially the middle of the height of the firebox, transversely extending water-circulating tubes arranged in the firebox spaced rearwardly from the upper edge of said wall, refractory slabs resting at their rear ends upon said tubes and at their forward ends upon said wall and provided on their undersides with depending projections adapted to retain said slabs in position; a refractory bridge member resting upon said slabs and spanning one of them, and provided on its underside with a recess permitting the easy removal of the slab above which the bridge member is placed, and an auxiliary wall supported on said slabs and said bridge member and rising to the crown sheet, said auxiliary wall being provided with a plurality of gas passages through which the gases of combustion may flow from the fuel bed to the flues.

7. In a locomotive boiler firebox, a refractory cross wall arranged in the forward end thereof, spaced rearwardly from the flue sheet and rising substantially to the middle of the height of the firebox, transversely extending water-circulating tubes arranged in the firebox, spaced rearwardly from the upper edge of the wall, refractory slabs resting at their rear ends upon said tubes and at

their forward ends upon said wall and closing the space between the tubes and the wall, and an auxiliary baffle supported by said tubes and resting upon said slabs, said auxiliary baffle being provided with a recess in its lower part which permits the free removal of one of said slabs.

8. In a locomotive boiler firebox, a refractory cross wall arranged in the forward end thereof and rising from the level of the grate to substantially the middle of the height of the firebox and spaced rearwardly from the flue sheet, transversely extending water-circulating tubes arranged in the firebox, spaced rearwardly from the upper edge of the wall, refractory slabs resting at their rear ends upon said tubes and at their forward ends upon said wall and having depending portions extending between the tubes and the wall and serving to hold said slabs in position, a refractory bridge member resting upon said slabs and spanning one of them, an auxiliary baffle supported on said slabs and said bridge member and rising therefrom to the crown sheet, said auxiliary baffle being provided with a plurality of relatively small gas passages through

which the gases of combustion may flow from the fuel bed to the flues, said refractory bridge member being provided with a ³⁰ tapered recess which permits the rear end of the slab above which it is placed to be raised a sufficient distance to free its depending projection from the refractory wall so that this slab can be removed from its ³⁵ position to give access to the space between the baffle and the flue sheet.

9. A locomotive boiler firebox and its grate, in combination with a cross wall at the forward end of the grate and composed ⁴⁰ of refractory bricks, transverse water circulating tubes extending across the firebox behind said wall, refractory slabs or bricks resting upon said tubes and wall, and refractory checker-work disposed upon said ⁴⁵ slabs.

In testimony whereof, I have hereunto set my hand this 22 day of Sept., 1913, in the presence of two subscribing witnesses.

JOHN P. NEFF.
